(57) CLAIM

I claim the ornamental design for a pair of brassiere inserts, as shown and described.

DESCRIPTION

FIG. 3 is a rear view of the right-handed insert of the pair of brassiere inserts;

FIG. 4 is a rear view of the left-handed insert of the pair of brassiere inserts;

FIG. 5 is a right side view of the right-handed insert of the pair of brassiere inserts;

FIG. 6 is a left side view of the left-handed insert of the pair of brassiere inserts;

FIG. 7 is a top view of the right-handed insert of the pair of brassiere inserts;

FIG. 8 is a top view of the left-handed insert of the pair of brassiere inserts; and,

FIG. 9 is a rear perspective view of both the right and left-handed brassiere inserts of the pair of brassiere inserts shown in an environment of use.

The dashed lines in FIG. 9 are shown for the environment only and form no part of the claimed design.
